Specification for Design.

Patented May 14, 1912.

Application filed March 4, 1912. Serial No. 681,636. Term of patent 7 years.

To all whom it may concern:

Be it known that I, CHARLES F. HUMPHREYS, a subject of the King of England, residing at Lancaster, in the county of Lancaster and State of Pennsylvania, have invented a new, original, and ornamental Design for Linoleum, Oil-Cloth, or other Printed or Inlaid Floor-Covering, of which the following is a specification, reference being had to the accompanying drawing, forming part thereof.

The figure illustrates a portion of lino-

leum, oil-cloth, and other printed or inlaid floor covering, showing my new design, the remaining parts being duplicates thereof.

I claim:

The ornamental design for linoleum, oil cloth, or other printed or inlaid floor covering, as shown.

CHARLES F. HUMPHREYS.
